TRANSFORMER

Le Roy H. Franklin, 427 Alicia Way, Los Altos, Calif.

Filed Aug. 3, 1961, Ser. No. 66,302

Term of patent 14 years

(Cl. D26—15)

FIG. 1 is a perspective view looking from the right front of my new design for a transformer, and

FIG. 2 is a similar perspective view, but from the left front thereof.

The rear of the transformer is substantially identical in appearance to the front, as illustrated.

I claim:

The ornamental design for a transformer, as shown and described.
